UNITED STATES PATENT OFFICE.

HARRY S. SPENCER, OF NORWOOD, OHIO, ASSIGNOR TO J. A. FAY & EGAN COMPANY, OF CINCINNATI, OHIO, A CORPORATION OF WEST VIRGINIA.

MORTISING-MACHINE.

SPECIFICATION forming part of Letters Patent No. 767,504, dated August 16, 1904.

Application filed December 4, 1903. Serial No. 183,694. (No model.)

To all whom it may concern:

Be it known that I, HARRY S. SPENCER, a citizen of the United States, residing at Norwood, in the county of Hamilton and State of Ohio, have invented certain new and useful Improvements in Mortising-Machines, of which the following is a specification.

My invention relates to mortising-machines of the stroke or pounding mortiser class, depending on the energy and force of the stroke given the mortising-chisel for performing the mortising operation, and has for its object the providing of peculiar construction of frame and bearings for the crank-shaft whereby the stroke is received by the frame for preventing vibration and affording rigidity; and the invention will be readily understood from the following description and claims and from the drawings, in which latter—

Figure 1 is a perspective view of a mortising-machine of the class mentioned employing my invention. Fig. 2 is a side elevation of the upper or crank-shaft end of the machine, showing my improved construction and showing the pitman in uppermost position. Fig. 3 is a perspective view of the upper or crank-shaft end of the column or frame with the movable parts and bearing-caps removed, showing the construction of the frame with the solid parts of the bearings thereon. Fig. 4 is a detail in section on the line $\alpha\alpha$ of Fig. 2, showing the means for securing the cap of the middle bearing of the crank-shaft; and Fig. 5 is a detail in section showing the crank connection with the pitman and outer bearing.

A is the column of the machine, on which a stock-supporting table B is suitably supported.

C is the chisel-ram, which in operation is rapidly reciprocated up and down in ways D on the column.

E is the chisel-spindle, carrying chisel F, adapted to be reversed in suitable manner—for instance, as more fully shown and described in Letters Patent No. 384,559, granted Bugbee and Danner June 12, 1888, for mortising-machine.

G is the crank-wheel, having crank-pin g'

and mounted on crank-shaft g' ; II, the pitman connecting the crank-wheel with the chisel-ram and spindle, and K K' a variable-stroke device for gradually lengthening the stroke of the chisel, as more fully shown and described in said above-mentioned Letters Patent. It is of course obvious that any other construction of pitman for connecting the crank-shaft with the chisel-ram may be employed.

In machines of the character described divested of my present improvement the reacting thrust from the chisel is conveyed through the chisel-ram, pitman, and crank-pin against the crank-wheel and crank-shaft, tending to throw that part of the crank-shaft next to the pitman upwardly, the greatest strain being on that part of the crank-shaft adjacent to the crank-wheel, said reacting thrust being also received by the removable caps of the bearings of the crank-shaft. In my present invention in order to counteract these tendencies and provide a construction in which the reacting thrust is directed toward an integral part of the column, being thereby received by and distributed in the column, I have provided a bearing for the crank-shaft adjacent to the crank whose solid or fixed part is rigid on the column above the crank-shaft, the removable box being below the crank-shaft, and have provided the column with an extension extending integrally outside the pitman above the crank-shaft and having an outer bearing whose solid or fixed part is above said crank-shaft for directing the reacting thrust of the chisel-ram toward the integral part of the column. The upper part of the column has two upwardly-extending standards L L', from one of which an extension L² is projected, the extension L² having a depending part L³, which for convenience may be a separate piece secured under said extension. The standards L L' form a U-shaped structure, in the mouth of which driving-pulley M is mounted on the crank-shaft. The standard L', extension L², and depending part L³ form an inverted-U-shaped structure, in the mouth of which the crank-wheel is located. The standards L L' and the depending part L³, with the connections be-

tween said parts, form a recumbent S-shaped structure, the middle web and ends of which support the bearings O P Q for the crank-shaft. The standard L' supports the bearing 5 O, having its solid or rigid part o above the crank-shaft, its removable cap o' being below said shaft, the removable cap being held in place by bolts o'', extending past the rigid part of said bearing through the top of the column. Below the bearing O the column has an aperture a for receiving the cap o'. The bearing Q on the gooseneck extension L² L³ 10 has its solid or rigid part q above the crank-shaft, the removable cap q' thereof being below the crank-shaft. The bearing P has its solid or rigid part p below the crank-shaft and its removable cap p' above the crank-shaft. It will thus be seen that the reacting thrust from 15 the pitman is received by the solid part of bearing O, the thrust being therefore received directly by the column. It will also be seen that the thrust being directed against the crank-shaft outside the bearing O the tendency is to throw the crank-pin end of the crank- 20 shaft upwardly and the pulley end of said shaft downwardly and that this tendency is counteracted and the thrust received by the solid or rigid parts of the bearings P Q. In order to counteract the tilting tendency of the 25 crank-shaft, I have provided oppositely-disposed bearings for that shaft.

The crank-pin g is secured to the crank-wheel by passing its threaded end through the web of the crank-wheel, a nut g² clamping the 30 pin in place. The crank-pin also has a stud g³ extending therefrom, having its journal in the bearing Q, the stud g³ substantially forming a part of the crank-shaft proper.

Having thus fully described my invention, 40 what I claim as new, and desire to secure by Letters Patent, is—

1. In combination, a mortiser of the character described, a crank-shaft and bearings therefor having their respective solid parts arranged on opposite sides of a horizontal plane.

2. In a mortising-machine of the character described, the combination with the column, chisel-ram and pitman, of a crank-wheel having a journaled crank-pin, a crank-shaft, an 45 overhanging extension from the column over the crank-wheel and having an outer bearing for the crank-pin journal, substantially as described.

3. In a mortising-machine of the character described, the combination with the column, chisel-ram, pitman, crank-shaft and crank-wheel and driving-pulley for the crank-shaft, of a recumbent S-shaped top for the column 50 having a bearing therein to each side of the crank-wheel, said driving-pulley being located in the upwardly-opening bend and said crank-wheel being located in the downwardly-opening bend of said reclining S-shaped top, substantially as described.

4. In a mortising-machine of the character

described, the combination of a column, a crank-shaft journaled at its top, a crank-wheel for the crank-shaft, said crank-wheel having a crank-pin, said crank-pin having a journal extension, a pitman operated by said crank-pin, a chisel-ram connected with said pitman, an inverted bearing for the crank-shaft adjacent to said crank-wheel, a gooseneck extension of said column projecting beyond said bearing over said crank-wheel, and an inverted bearing in the end of said extension for said crank-pin journal extension, substantially as described. 75

5. In a pounding mortising-machine, the combination with the column, chisel-ram and pitman, of a crank-shaft for the pitman, said column having an extension whose integral part projects outside said pitman above said crank-shaft, and an outer bearing on said extension having a part above said crank-shaft 80 fixed with relation to said integral part, substantially as described. 85

6. In a pounding mortising-machine, the combination of a crank-shaft having a crank, a bearing therefor adjacent to said crank having its solid part above and another bearing therefor having its solid part below said crank-shaft. 90

7. In a pounding mortising-machine, the combination of a column, a crank-shaft having a crank, a bearing for said crank-shaft adjacent to said crank whose solid part is rigid on the column above said crank-shaft, a removable cap for said bearing below said crank-shaft, and a second bearing for said crank-shaft whose solid part is rigid on the column below said crank-shaft and a removable cap 100 for said last-named bearing above said crank-shaft, substantially as described. 95

8. In a pounding mortising-machine, the combination with the crank-shaft, chisel-ram and pitman, of oppositely-disposed bearings for the crank-shaft having their solid parts respectively above and below the crank-shaft for receiving the tilting strain on said crank-shaft, substantially as described. 105

9. In a pounding mortising-machine, the combination with the column, chisel-ram, pitman, crank-shaft and driving-pulley for the crank-shaft, of a recumbent S-shaped top for 110 the column, said driving-pulley being located in the upwardly-opening bend and the crank of said crank-shaft being located in the downwardly-opening bend of said reclining S-shaped top, and relatively inverted bearings 115 in the ends and an inverted bearing in the middle web of said reclining S-shaped top for said crank-shaft. 120

In testimony whereof I have signed my name hereto in the presence of two subscribing witnesses. 125
